2,194,233

STOPPER

Joseph Renka, Jr., New York, N. Y.

Application July 23, 1938, Serial No. 220,979

1 Claim. (Cl. 215—48)

This invention aims to provide a novel stopper for a vacuum bottle, so constructed that it will not readily lose its shape, become foul, transfer the taste or smell of one liquid to a different liquid, or have the disadvantages attendant upon using a vacuum bottle stopper made of cork which is exposed to the contents of the bottle.

Another object of the invention is to provide a stopper which will have not only the characteristics above mentioned but, as well, will present a novel cushion which will be soft to the fingers, when the stopper is shoved into a bottle, the stopper at the same time being compressible and expandable under pressure, to effect a more perfect closure.

Another object of the invention is to provide a stopper for vacuum bottles which may be assembled in a simple and novel way, without the use of tools, it being possible to use the core repeatedly, if the operator wishes.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in side elevation, a vacuum bottle equipped with a stopper constructed in accordance with the invention, a portion of the bottle being broken away;

Fig. 2 is a longitudinal section of the stopper depicted in Fig. 1, in condition for use;

Fig. 3 is a diagrammatic view illustrating the process by which the stopper shown in Fig. 2 may be constructed;

Fig. 4 is a top plan of the stopper delineated in Fig. 2;

Fig. 5 is a side elevation showing a modified form of the invention;

Fig. 6 is a longitudinal section of the stopper forming the subject of illustration in Fig. 5.

The numeral 1 marks a vacuum bottle, used to keep hot liquids hot and cold liquids cold, the structure being recognized readily from the foregoing description, although the trade-mark name, if it could be used in this specification, would identify the article more directly. The bottle 1

has an external thread 2 on which a cap (not shown) is screwed to place.

The stopper forming the subject matter of this application may include a core 3, which may be a cork, the term "cork" defining the material preferably used, rather than indicating that the core 3 is a stopper. It is proposed to locate the core 3 within a casing 4, having a bottom 5, the casing being supplied at its upper end with an inwardly extended annular rib 6 defining an opening 7, the casing embracing the core 3 closely, and the rib 6 resting tightly on the upper end of the core 3. The casing 4 preferably is made of resilient rubber.

In the making of the stopper, the casing 4 is turned inside out, as in Fig. 3, and the bottom of the casing is placed against the lower end of the core 3, the casing being inverted. The casing 4 is stripped upwardly over the core 3, from the position of Fig. 3 to the position of Fig. 2, the rib 6 snapping over the upper end of the core 3, and the article, thus, assuming the completed condition of Fig. 2.

In Figs. 5 and 6, parts hereinbefore described have been designated by numerals already used, with the suffix "a". In this form of the invention, the core 3a has a reduced neck 8 defining a shoulder 9 in the core. The article is assembled, preferably, after the manner of Fig. 3, the rib 6a snapping downwardly on top of the shoulder 9 and embracing the neck 8 closely. The casing 4a is made out of resilient rubber, like the casing 4, the core 3a, however, being made out of rubber which is somewhat more resilient and softer than the rubber out of which the casing 4a is constructed.

In seating the stopper of Figs. 5 and 6 in the neck of the vacuum bottle 1, pressure may be applied to the compressible neck 8 of the core 3a. The upstanding portion of the neck 8 forms a cushion which makes this operation easy on the fingers, a consideration which is desirable especially in view of the fact that vacuum bottles often are stoppered by women or children. Moreover, when the cap of the vacuum bottle 1 (the cap being absent from the drawing) is engaged with the thread 2, the cap may be pressed on the neck 8, and as the neck 8 is thrust down, the core 3a will exert an increased expanding pressure on the casing 4a, thereby causing the stopper to make a more perfect closure in the neck of the bottle.

The neck 8 must extend above the rib 6a, in order to provide the cushion hereinbefore referred to. The neck 8 is short enough so that, when the

stopper is wedged tightly in a bottle, the operator cannot lay hold of the neck and pull the core 3a out of the casing 4a. Moreover, the neck 8 carries no ring or similar device, by which an operator might the more readily drag the core 3a out of the casing 4a. The device cannot be characterized by the negative statement that the neck 8 does not carry a ring or other pulling handle, but, as to the absence of the handle, the article 10 may be characterized positively by the statement that the upper end surface of the neck 8 constitutes the uppermost portion of the stopper.

Whether the form shown in Fig. 2 or the form shown in Fig. 6 is used, the core is not exposed 15 to the liquid in the bottle, and the advantages set forth in the opening portion of this specification will be consummated. A shielding of the core from contact with the contents of the bottle is peculiarly desirable when the cork core 3 of Fig. 2 20 is used.

Having thus described the invention, what is claimed is:

A stopper for vacuum bottles, comprising a resilient core provided at its upper end with a reduced upstanding neck defining a transverse 5 shoulder, and a resilient casing enclosing the core and provided at its upper end with an inwardly projecting annular rib forming an opening, the rib overhanging and engaging the shoulder, the rib embracing the neck closely, the neck being 10 of the same cross sectional area as the opening, throughout the entire height of the neck, the neck extending upwardly above the rib a distance approximating the thickness of the rib, to form a cushion which facilitates the seating of the 15 stopper, the core being more resilient than the casing, the upper end surface of the neck constituting the uppermost portion of the stopper.
